DESIGN FOR A TOY ANIMAL

Albert Ernest Brett Rose, London, England

Application September 25, 1936, Serial No. 65,001
In Great Britain May 29, 1936

Term of patent 7 years

To all whom it may concern:

Be it known that I, Albert Ernest Brett Rose, a subject of the King of Great Britain, residing at London, England, have invented a new, original, and ornamental Design for a Toy Animal, of which the following is a specification, reference being made to the accompanying drawing, forming part thereof.

I claim:—

The ornamental design for a toy animal, as shown.

ALBERT ERNEST BRETT ROSE.
